US0D1075128S

(12) United States Design Patent (10) Patent No.: US D1,075,128 S
(45) Date of Patent:  May 13, 2025

(54) LAMP

(71) Applicant: Outside In (Cambridge) Limited,
Cambridge (GB)

(72) Inventors: Jonathan Cridland, Peterborough
(GB); Steven Lourdes, Cambridge
(GB); James Benham, Newcastle (GB)

() Term: 15 Years

(21) Appl. No.: 35/520,531

(22) Filed: Mar. 22, 2024

(80) Hague Agreement Data

Int. Filing Date: Mar. 22, 2024

Int. Reg. No.: DM/236196

Int. Reg. Date: Mar. 22, 2024

Int. Reg. Pub. Date: Apr. 12, 2024

(51) LOC (15) Cl. 26-05

(52) U.S. Cl.

USPC D26/108; D26/61

(58) Field of Classification Search

USPC D26/51, 56, 60-66, 93, 104, 106-108;
D24/209, 210

CPC .. F21S 6/002; F21V 33/0064; F21V 33/0068;
F21W 2131/20; F21W 2131/202

(57) CLAIM

The ornamental design for a lamp as shown and described.

DESCRIPTION

Lamp

Fig. 1.1 is a front view of the lamp showing the new design;

Fig. 1.2 is a back view thereof;

Fig. 1.3 is a left view thereof;

Fig. 1.4 is a right view thereof;

Fig. 1.5 is a front perspective view thereof;

Fig. 1.6 is a back perspective view thereof; and

Fig. 1.7 is a bottom view thereof.

The portion of the lamp shown in broken lines on the bottom view forms no part of the claimed design.

1 Claim, 7 Drawing Sheets
